(No Model.)

W. M. RAPE.

COMBINED COTTON PLANTER AND FERTILIZER DISTRIBUTER.

No. 423,811.

Patented Mar. 18, 1890.

UNITED STATES PATENT OFFICE.

WILLIAM M. RAPE, OF NOTASULGA, ALABAMA.

COMBINED COTTON-PLANTER AND FERTILIZER-DISTRIBUTER.

SPECIFICATION forming part of Letters Patent No. 423,811, dated March 18, 1890.

Application filed October 24, 1889. Serial No. 328,035. (No model.)

To all whom it may concern:

Be it known that I, WILLIAM M. RAPE, a citizen of the United States, residing at Notasulga, in the county of Tallapoosa and State 5 of Alabama, have invented certain new and useful Improvements in Combined Cotton-Planters and Fertilizer-Distributors, of which the following is a specification, reference being had therein to the accompanying drawings.

This invention relates to certain improvements in combined seed-planters and fertilizer-distributors; and it has for its objects to provide for operating the discharge mechanism 15 for the seed and the mechanism for distributing the guano simultaneously in a simple and effective manner, and also to provide an improved coverer that will automatically adjust itself to the surface over which the 20 planter passes, as more fully hereinafter explained.

The above-mentioned objects I attain by the means illustrated in the accompanying drawings, in which—

25 Figure 1 represents a side elevation of my improved planter and distributor; Fig. 2, a longitudinal vertical sectional view thereof. Fig. 3 represents a detached perspective view showing a portion of the cover in detail, and 30 Fig. 4 a transverse vertical sectional view taken centrally through the end hopper.

Referring to the drawings, the letter A indicates a rectangular frame which carries the hoppers B C, one located near each end thereof.

35 The letter D indicates two inclined standards secured to the sides of the frame A, their lower ends terminating below the frame in such position as to equally balance the weight of the hoppers upon the journals of the shaft

40 E of the wheel E', the said journals having their bearings in the lower ends of the standards before mentioned. The upper ends of said standards are provided with a cross-head F, to which are secured the beams G, forming 45 the handles of the planter, the forward ends of said beams being rigidly secured to the forward portion of the frame A. The hoppers B C are constructed with open bottoms, and are provided with armed distribut-

50 ing-disks H I, mounted upon shafts K L, which have crank-arms M N on the ends projecting at one side.

The axle of the wheel E' is formed with crank-arms P, which are connected to the crank-arms N by means of connecting-bars 55 R, so as to give motion to the shaft L. The connecting-bars R are connected to the crank-arms M by means of connecting-bars S, so that the distributing-disks H I will be operated simultaneously.

The letter T indicates the coverer. This consists of a cross-bar U, secured to the rear ends of the arms V W, which are pivoted to the frame A at their forward ends just above the journal-bearings of the shaft of the wheel 60 E. The rear ends of the said arms are bent inwardly, the bent ends of the arms V being bolted or otherwise secured to the rear of the cross-bar U near its lower edge and the bent ends of the arms W being secured to the front 65 edge of the said bar U near its upper edge. Bolted to the front of the cross-bar U and secured by the bolts, which fasten the bent ends of arms W to the said cross-bar, are the shares or blades X, which straddle the row of seed 70 as they are dropped and cover the same.

The respective hoppers are provided with conducting-tubes Z A', leading from the bottom thereof, and in front of the conducting-tube A' is located a share or opening blade 75 B' to produce the furrow, into which the seed and the fertilizer are subsequently dropped.

The seed-hopper at its bottom is provided with a longitudinal slot and a longitudinal dividing-bar C', forming two parallel longitudinal openings, through which the seed pass to the tube A', the seed being carried down through said openings by means of the radial arms D', arranged alternately in two rows on the distributing-disk I. This arrangement 80 insures the delivery and proper spacing of the seeds, preventing any possibility of skipping in dropping the seeds. As thus constructed, it will be perceived that the weight of the respective hoppers is equally balanced 85 upon the shaft of the wheel upon which the frame is mounted. The oblique braces not only serve as bearings for the axle of the wheel, but also to support the handle-beams, which being attached to the forward end of 90 the frame afford a means of accurately guiding the planter. The bars connecting the respective crank-shafts of the hoppers and driving-wheel serve to simultaneously operate the 95 100

same, insuring the uniform dropping of the seed and the dropping of the fertilizer over the same.

By the peculiar construction of the coverer 5 it will be seen that the shares thereof will run over the ground and will automatically adjust themselves to irregularities thereof, yielding when passing over stumps and other obstructions, the cross - bar being insured 10 against twisting or becoming misplaced by reason of its forward and rear connections to the bent arms V and W.

Having thus described my invention, what I 15 claim, and desire to secure by Letters Patent, is—

1. The combination, in a planter, of the rectangular frame, the inclined standards projecting below the frame, the wheel having its bearings in the lower ends of said standards, 20 and the handle-beams secured to the forward end of the frame and to the upper cross-bar

secured to the inclined standards, substantially as and for the purposes specified.

2. The combination, with the frame of a planter, of the arms pivoted thereto having 25 their rear ends bent inwardly and the cross-bar to which the said ends are secured, respectively, to the front and rear thereof, substantially as specified.

3. The combination, with the cross-arm of 30 the coverer, of the arms having the bent ends thereof secured, respectively, to the front and rear of the cross-arm, and the shares or blades secured between the forward arms and said cross-arm by the same bolts, substantially as 35 specified.

In testimony whereof I affix my signature in presence of two witnesses.

WILLIAM M. RAPE.

Witnesses:

W. H. HARTLEY,
I. F. SIGGIRS.
